UNITED STATES PATENT OFFICE.

FRANKLIN W. KREMER, OF WADSWORTH, OHIO, ASSIGNOR TO THE GARFIELD INJECTOR COMPANY, OF SAME PLACE.

AUTOMATIC LOCOMOTIVE-INJECTOR.

SPECIFICATION forming part of Letters Patent No. 374,975, dated December 20, 1887.

Application filed April 15, 1887. Serial No. 234,944. (Model.)

To all whom it may concern:

Be it known that I, FRANKLIN W. KREMER, a citizen of the United States, residing at Wadsworth, in the county of Medina and State 5 of Ohio, have invented certain new and useful Improvements in Automatic Locomotive-Injectors, of which the following is a full, clear, and exact description.

This invention relates to that class of devices for supplying steam-boilers with water represented in the United States Letters Patent No. 335,227, granted to me and dated February 2, 1886; and one special object of the present invention is to provide an injector of such a 15 character as to be capable of lifting the water directly after being used as a heater, or when the suction or supply pipe becomes heated to such a temperature as to render it impossible to create a vacuum.

Other objects of the invention are to perfect 20 the construction of certain details of the apparatus.

The invention consists in an injector constructed and operating in the manner substantially as hereinafter particularly set forth and claimed.

In the accompanying drawings, in the several figures of which like parts are similarly designated, Figure 1 is a perspective view of 30 sufficient of a locomotive-engine and its tender to illustrate the application of my injector. Fig. 2 is a vertical longitudinal section of the injector, and Fig. 3 is a sectional elevation of a detail.

It is to be understood that an injector to 35 meet the requirements of a locomotive must be so constructed that it can be used to heat the water in the tender or tank in cold weather, in addition to its primary function of supplying water to the boiler. In the ordinary locomotive-injector it frequently occurs that after the instrument has been employed as a heater it becomes necessary to allow the instrument to cool before a vacuum can be produced to 45 lift the water and the instrument restarted, delays thus ensuing which frequently are serious. In the present invention the difficulties just mentioned are entirely obviated, and the machine can be started instantly, regard-

less of the temperature of the water in the supply-pipe.

The injector may be of the construction shown in the patent hereinbefore referred to. In Fig. 1 I have designated the injector as a whole by the letter A. The steam-connection 55 with the boiler is designated B. The water-connection between the boiler and injector is designated C, and the water-supply pipe, connecting the injector with the tender or tank, is designated D, while E designates the overflow. The controlling-valve is designated F, the steam-valve G, and the combined overflow and frost valve or plug is designated H. I also prefer to use a supplemental check-valve, I, in conjunction with the check-valve a. 65

The valve G has certain details of construction, which will be hereinafter more particularly set forth; but for the purpose of fully explaining the first part of my invention, I will now proceed to describe the operation of the 70 injector constructed and arranged substantially as just set forth.

To operate the injector as a heater the valve H is screwed down so as to close the overflow. The spindle b of this valve is provided with a 75 screw-thread, e, of large pitch, so as to render said spindle quick-acting. Steam is now admitted by opening the valve G, and passes thence through the tube e and chamber f and pipe D to the tender or tank, thus warming 80 the water therein to the extent desired. Now, to start the injector under these conditions, the valve G is opened to admit sufficient steam to drive the water out of the pipe D back into the tank, and then by quickly opening the 85 valve H the steam is permitted to escape at the overflow, thus relieving the pressure in the supply-pipe D and permitting the water to enter the said pipe D by virtue of its own gravity. The water, in passing from the tank or 90 tender to the lowest point of the supply-pipe D, obtains sufficient velocity to cause it to flow into the chamber f, where it is acted upon by the steam issuing from the tube e, the water being thereby accelerated and the jet established sufficient to deliver the water to the 95 boiler. For the perfect operation of the apparatus provision must be made for the free

escape of steam, and this I accomplish by the use of the perforated plate *g*.

It will be seen that the principle employed in the operation of this injector is entirely different from that of the ordinary injector, and is only applicable to an automatic injector of the description set forth, in which special provision is made for the free escape of steam at the overflow. Ordinarily there is no communication of this sort, and the steam passes only through the combining-tube. In machines where this is the case the exhaust would be too sluggish, and the water would not obtain sufficient velocity in entering the pipe *D* to raise it to the chamber *f*.

By my construction, herein set forth, the water can be lifted no matter how highly heated.

The steam-valve *G* has a stem, *h*, on which the plug or valve proper, *i*, is arranged. This stem *h* has a hand-wheel, *j*, for operating it. The stem *h* has a screw-threaded bearing in a boss, *k*, arranged upon a yoke, *l*, and this yoke terminates in a screw-threaded nut, *m*, by which the yoke is secured in the valve-shell *o*, the stem being provided with a gland, *p*, which, by means of the yoke, is accessible from the outside for operation by means of a wrench, thus obviating the necessity of removing a bonnet to get at the gland.

What I claim is—

1. A locomotive-injector having a steam-inlet and connections with the steam-space of

the boiler, a valve therein, a water-inlet, and connections with the tender, a controlling-valve interposed between these two inlets, a combining-tube, boiler-connections for introducing feed-water, and a check-valve interposed between the boiler and overflow-valve, combined with a quick-acting overflow-valve, substantially as and for the purpose set forth.

2. An injector comprising a steam-inlet and valve therein, a water-inlet, a controlling-valve, check-valves *a* and *I*, a combining-tube, and a quick-acting overflow-valve, combined and arranged substantially as set forth.

3. An automatic injector for locomotives, comprising a steam-inlet and a water-inlet, an interposed steam-supply pipe, a combining-tube, a quick-acting overflow-valve, and auxiliary steam-passages between the combining-tube and boiler, substantially as described.

4. A valve, *G*, having a threaded stem, combined with a yoke provided with a threaded boss at one end engaged by said threaded stem and an internally and externally threaded nut, *m*, at the other end, and a gland accessible from the outside of the yoke and valve, substantially as described.

In testimony whereof I have hereunto set my hand this 14th day of April, A. D. 1887.

FRANKLIN W. KREMER.
